UNITED STATES PATENT OFFICE.

JESSE FULENWIDER, HARRY FULENWIDER, EDWARD W. ROBINSON, AND HARRY S. NORRIS, OF SAVANNAH, GEORGIA, ASSIGNEES TO SAID HARRY FULENWIDER AND JESSE FULENWIDER.

RIDGE-CAP-FORMING MACHINE.

Application filed June 28, 1926. Serial No. 119,144.

The object of this invention is to provide a machine for forming ridge caps employed in connection with sheet metallic roofing,—the machine including a forming plate and a cooperating element or elements by means of which the plate or strip of sheet metal is first bent into channel form, and a plurality of rolls for forming the flanges of the channel in the manner required in the finished product.

A further object is to provide a roll rotatable about an axis extending transversely of the path of travel of the sheet and having a convex central portion engaging the inner wall of the channel, and a plurality of cooperating rolls mounted on axes inclined with reference to the axis first named, the cooperating rolls having a circumferential channel or concave portion for engaging the outer surface of the sheet.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 shows the rolls and mounting means therefor in elevation, the elements of the base being in vertical transverse section.

Figure 2 is a section on line 2—2 of Figure 3.

Figure 3 is a view of the machine in side elevation.

Figure 4 is a perspective view, showing certain of the forming elements.

A shaft 10 mounts a driving pulley 11 on one end, and on the other end a gear wheel 12 adapted to mesh with gear wheel 13 mounted on a shaft 14 which in turn mounts lower forming roll 15.

The roll 15 includes the convex central portion or circumferential portion 16, and tapered annular shoulders 17, and this roll carries bevelled gear wheel or pinions 18 and 18' thru which drive is imparted from shaft 14 to bevelled gear wheels 19 and 19'.

The wheels last named are formed with the rolls 20 and 21 each having an annular groove, such as 22, and an annular portion 23 constituting a face for cooperation with tapered surfaces 17 of roll 15. The rolls 20

and 21 are mounted on axles or shafts 24 and 25, these being inclined as shown, in Figure 1, and the angle of inclination being such that the surfaces 23 are directly opposite the tapered annular shoulders 17, and the flanged or annular portions 26 of the upper rolls are opposite the shoulders 27 of roll 15.

The shafts 24 and 25 extend thru a U shaped bracket 30 having angular end portions 31 and 32, and thru the latter screw bolts such as 33 extend and engage the nuts on bolts 24 and 25, lock nuts being shown at 34. The shaft 10 is mounted in bearings 36 and 37 supported by brackets 38, 39, carried by longitudinal channel bars 40 and 41 constituting a base.

The shafts 24 and 25 are mounted in brackets 41' and the latter are slidable or adjustable with reference to brackets 42 carried by or formed with elements 38 and 39. Adjustment is provided by means of screws 44 passing thru the end portions 45 of elements 41', and retained by lock nuts 46 and 47.

A bar 50 extends longitudinally of the machine, mounts strip 50' and is mounted on V-shaped brackets 51 carried by channel bars 40 and 41 of the frame or base. A forming plate 53 extends over bar 50 and is spaced therefrom as shown in Figure 2. The sheet of metal roofing being formed passes between bar 50 with its strip 50' and plate 53, and is guided between pins 54 and 55 on bar or brace 56. The sheet is further guided by bars 57 and 58, and is formed by the structure of Figure 4 into an inverted V channel, from which it passes to the structure of Figure 1. The plate 53 may be formed as illustrated in Figures 3 and 4, being provided with a curved edge at 53', on each side thereof, and plate 53 is supported by the V-shaped bracing elements 59 having an offset at 59' to provide a space 60 thru which the plate passes, in the forming operation.

Having thus described the invention, what is claimed is:

1. In a ridge cap forming machine, a plurality of rolls each provided with an annular channel and with plain annular work engaging surfaces, these rolls being rotatable about axes inclined with reference to each other, and a third roll mounted between the

rolls first named and having plain work engaging surface and a central circumferential convex portion spaced from the walls of the channels of the rolls first named.

2. In a ridge cap forming machine, a plurality of rolls each provided with an annular channel and rotatable about axes inclined with reference to each other, and a third roll mounted between the rolls first named and 10 having a central circumferential convex portion spaced from the walls of the channel of the rolls first named, the third roll including tapered annular shoulders and the remaining rolls having cylindrical portions 15 opposite said annular shoulders.

3. In a ridge cap forming machine, a plurality of rolls each provided with an annular channel and rotatable about axes inclined with reference to each other, and a third roll 20

mounted between the rolls first named and having a central circumferential convex portion spaced from the walls of the channel of the rolls first named, said third roll including outer beveled surfaces and the channelled rolls including surfaces complementary to the beveled portions, gear wheels carried by the third roll, and gear wheels rigid with the rolls first named and driven by the gear wheels on the third roll.

30 4. In a ridge cap forming machine, a plurality of rolls each provided with an annular channel and rotatable about axes inclined with reference to each other, and a third roll mounted between the rolls first named and 35 having a central circumferential convex portion spaced from the walls of the channel of the rolls first named, the third roll including tapered annular shoulders and

the remaining rolls having cylindrical portions opposite said annular shoulders, and 40 means for adjusting the position of the rolls first named.

5. In a ridge cap forming machine, a plurality of rolls each provided with an annular channel and rotatable about axes inclined with reference to each other, and a third roll mounted between the rolls first named and having a central circumferential convex portion spaced from the walls of the channel of the rolls first named, the third roll including tapered annular shoulders and the remaining rolls having cylindrical portions 50 opposite one of the annular shoulders on each side of the third roll, and having flanges adjacent to the cylindrical portions and opposite the other tapered annular shoulder of the third roll.

6. In a ridge cap forming machine, a bar extending longitudinally of the path of movement of a sheet to be formed, a forming plate of inverted channel shape mounted in spaced relation to the bar and above the latter, a lower forming roll mounted beyond the plate and having a convex surface, and upper forming rolls having annular channels therein, the channel portions being on opposite sides of the convex portion of the lower roll, the upper rolls being rotatable above axes converging in an upward direction.

In testimony whereof we affix our signatures.
